UNITED STATES PATENT OFFICE.

JAMES E. WESTLAKE, OF ALBUQUERQUE, TERRITORY OF NEW MEXICO.

CONCENTRATING-MACHINE.

SPECIFICATION forming part of Letters Patent No. 328,627, dated October 20, 1885.

Application filed March 14, 1885. Serial No. 158,864. (No model.)

To all whom it may concern:

Be it known that I, JAMES E. WESTLAKE, of Albuquerque, county of Bernalillo, and Territory of New Mexico, have invented a new and useful Improvement in Concentrating-Machines, of which the following is a full, clear, and exact description, reference being had to the accompanying drawings, making part of this specification.

10 My invention relates to an improvement in machines for separating, concentrating, and collecting gold contained in "placers," either with or without the use of water; and it consists in a novel construction of screen-cylinder having buckets and feeders; in a novel construction of pulverizer, and of the sluice, scrapers, and scraper-beam connected therewith, and in the means for actuating the latter; in the combination, with the sluice, of a 15 settling-tank, water-supply tank, and automatic feed-water attachment; in the combination, with the settling-tank, of a spiral amalgamating-plate for the collection of "flour" gold in its passage through or from said tank, 20 and in certain details of construction and arrangement of parts, hereinafter fully described and claimed.

In the accompanying drawings, Figure 1 represents a side elevation of my improved machine; Fig. 2, a plan view of the same; Fig. 3, a sectional view of the screen-cylinder; Fig. 4, a side elevation of the concave apron, and Fig. 4^a a face view of the same; Fig. 5, a side elevation of one of the scrapers with the spring 35 attached; Fig. 6, a side elevation of the cam-plate; Fig. 7, a perspective view of a portion of a scraper-beam and parts connected therewith, and Fig. 8 a vertical section through the settling and water-supply tanks and the spiral 40 amalgamating plates and tubes.

A A' represent an upright frame-work, of any suitable construction, to support the working parts, hereinafter described, in one end of which is secured a semi-cylindrical 45 tank, B, within which is placed a cylindrical screen, B', which, when in use, is covered by a semi-cylindrical cover (not shown) similar in form to the tank B, and which, in connection with the latter, serves to inclose the screen B'. 50 The latter is provided with hollow cylindrical trunnions B² B³, through one of which, B², the

placer-earth is fed into the screen, the coarser parts of which, such as will not pass through the screen, are conveyed through the latter by means of a spiral internal thread or screw, b, 55 (see Fig. 3,) and pass out through the opposite hollow trunnion, B³. The trunnions B² B³ rest and rotate upon friction-rollers a a, mounted in suitable bearings on the frame A, and motion is imparted to the cylinder by 60 means of a pulley or band wheel, C', and band C² connecting it with a shaft, C, which, for the purpose of this description, may constitute the first or main driving-shaft of the machine, mounted in suitable bearings in the frame, and 65 to which motion may be imparted in any suitable manner. The screen-cylinder is provided on its periphery at each end with a spiral thread, b' and b², one arranged to feed to the right and the other to the left, and both to 70 toward the center of the length of the cylinder, where is arranged a band, b³, of metal or other suitable material, to which, at suitable and regular intervals, a series of buckets, b⁴, are secured, which serve to take up the screened 75 earth carried to them by the spirals b' and b² and to carry the same up over the screen, discharging it through an opening in the screen-casing upon a concave apron, D, secured to the inner side of the tank B. This apron is 80 shown in section and inner face view in Figs. 4 and 4^a, and is provided with a series of flat springs, d d', curved in ogee shape, as shown in the sectional view, and arranged in transverse rows, those in one row, d, breaking joint 85 with or overlying the spaces between those of the adjoining row, as shown in the face view, Fig. 4. The lower end of this apron hangs down within the forward or adjacent end of the sluice E, with the springs d d' pressing lightly against or resting in close proximity to the surface of a grinding wheel or cylinder, F, mounted in suitable bearings in the frame A, and which, through the arrangement of the apron-springs d d', as described, 95 is caused to act upon all the material passing over the apron, and thereby to assist in pulverizing the same.

The pan or sluice E is composed of two sides and a bottom plate, the latter curved 100 upward at its end adjacent to the screen-cylinder tank, and into which the lower end of the

concave or apron D projects, to conform somewhat in shape to the latter and to the grinding-cylinder F dipping therein, as shown. The bottom of this sluice-pan is by preference made 5 of corrugated sheet metal, as shown at e, and may also be electro-silver plated to give it an amalgamating action; but this is not essential. The pan or sluice is set at an inclination to the bed-frame of the machine, its rear or discharge end being raised for the two-fold purpose of getting the resistance of gravity to the onward movement and discharge of the heavier particles or grains of gold, and also of raising the bottom of the sluice for some distance in advance of the point of discharge 15 above the water-level in the sluice, (indicated by dotted line at e'), and thereby causing the latter to flow back and preventing its escape and waste.

20 The sluice-pan is suspended in the frame A by means of pendent rods e² e³, two or more on each side, and secured at their lower ends to cross-bars e⁴ e⁵, on which the sluice-pan rests, the arrangement being such as to adapt the 25 pan to swing freely in the frame.

20 Motion is imparted in a longitudinal direction to the sluice-pan by means of eccentrics f' f' on the shaft f of the grinding-wheel F, and rods f², connecting said eccentrics with 30 the bar e⁵, as shown, or in other suitable manner, and a lateral reciprocation is imparted to the sluice-pan by means of a short crank-arm, f³, on the shaft f, a pitman, f⁴, extending thence to an arm on a longitudinal rock-shaft, 35 F', mounted in suitable bearings in the frame A, and provided with arms f⁵ and f⁶, from which connecting rods extend to suitable points of attachment to the sluice-pan. The throw given to the pan E in either direction 40 will be slight, its movement not necessarily exceeding half an inch in a longitudinal direction, and an inch (more or less) in a transverse direction, and the two combined serve to give to each point throughout its entire 45 surface a gentle movement in an elliptical path, a movement which has been found in practice to be very effective in producing a separation of the lighter and heavier particles of matter contained in the pan.

50 Above the pan E are two bars, G, of angle-iron or other suitable material, secured to uprights of the frame or other suitable points of support on each side of the sluice-pan, and each provided at each end with a cam-plate or 55 tramway, G'. The construction of these plates is shown in Figs 6 and 7, each being provided with a bent or angular rail, g', pivoted at the inner end of its horizontal upper arm to the plate G', with the foot of its outer inclined end, 60 g'', resting lightly on the horizontal ledge g of the angle-iron G. Just inside of the pivoted inner end of the rail g' is arranged a tilting block or rail, g'', pivoted at or near its center to the plate G', and with its end adjacent to g' upheld by a light spring, g³, the functions of 65 which parts will be explained. Between the bars or rails G are two parallel bars, H H', con-

stituting what I term the "scraper-beams," from the fact that the scrapers hereinafter described are connected with and operated by them. These bars are connected at or near the center of their length by a strong cross-bar or shaft, I, and a pitman, I', extending thence to a crank-wrist on a shaft, C³, geared to and operated from the shaft C, which serves to impart a longitudinal reciprocation to the scraper-beams.

In suitable lugs or ears on the bars H are secured two rods or transverse shafts, h h the ends of which may, if desired, be provided with 80 friction-rollers and overhang the ledge or rail g, rolling thereon in the outward movement of the scraper-beam. As the ends of these rods or trunnions h pass outward, they lift and pass under the ends g'' of the bent rails g', and the 85 latter dropping down behind them cause the rods h h' in the inward or return movement of the scraper-beam to ride upward, carrying the scraper-beam with them and lifting the scrapers secured thereto up out of and over the material in the sluice. Just at the completion of the inward throw of the scraper-beam the ends of the rods h h' pass off from the inner ends of the rails and upon the adjacent end of the 90 tilting rails g'', and the weight of the scraper-beam and scrapers being sufficient to overcome the tension of springs g³, the rails g² are tilted and permit the scraper-beam to descend and the roller or ends of rods h to pass easily and lightly therefrom to the ledge g as the scraper-beam starts upon its outward effective throw. The scraper-beam and its supports 95 are set above and in an inclined plane parallel with the sluice, and the scrapers are made somewhat less in width than the latter, to accommodate the lateral vibrations of the sluice and permit the water to escape and flow back at the sides thereof.

100 The scrapers k are formed of angle-iron, as indicated, and are secured to spring-holders k', one at each end, the latter being made in loop or U shape, and preferably with one or more coils at the bend to give increased elasticity to the springs, and are secured to the inner sides of the bars H by means of a pin at 105 k² entering the coil, and a second pin or staple, k³, securing the end of its upper arm to the beam. The scrapers are further connected with the beam or side bars, H, by chains l, connecting them at each end with hooks or pins 110 on the bars H, said chains serving to limit the downward movement of the scrapers, while the springs allow them to yield upward to pass any unusual obstruction in their path. The scrapers may be adjusted in height by means 115 of the linked chains l, which may be lengthened or shortened as desired.

120 The intermitting action of the scrapers due to the action of the cam-plates or tramways on the scraper-beam will be readily understood, and 125 is found very effective in practice in permitting the return and washing action of the water in the sluice upon the "slime" or placer earth therein.

Upon one side of the sluice and its supporting-frame is arranged a "settling" tank, M, when water is to be used, and this is located with reference to the screen-cylinder tank B 5 and the sluice E, and so connected with them by pipes m and m' that the water may pass freely from one to the other for preserving a uniform water-level in all. The pipe m', connecting the settling-tank and the sluice, 10 should be of flexible material to permit the vibration of the latter, as described.

The tank M is shown with a central transverse partition at M' dividing it into two compartments, connected by a tube, N, open at its 15 ends, and in which is placed a spiral plate, N', electro-silver plated to give it an amalgamating surface, adapting it to take up and retain the flour gold passing from the first through into the second compartment; but this division of the settling-tank is not essential, as the spiral amalgamating-plate may be placed at one end of the tank in a cylindrical chamber, O, opening into the tank at one end, and at its other having the pipe m connecting with the 20 screen-cylinder tank attached to its other end, as shown. Both arrangements of spiral amalgamating-plates may, however, be used, if desired; but when only one is used, that at N' at the entrance to the pipe leading to tank B is preferred, as it gives increased settling-surface to 25 tank M in advance of the passage of the water over the spiral plate.

Directly over or on a higher plane than the settling-tank M is arranged a feed-water tank, 30 P, connected by a pipe, p, either with the tank M or with the sluice-pan, or both, the feed or flow of the water through said pipe being controlled by means of a check or other suitable form of valve, q, which is connected with a 35 float, Q, in the tank M, so arranged that whenever the water in the latter falls below the desired level the valve q will be lifted or opened to allow the water to flow out through pipe p, and when the water again reaches the desired 40 level the valve will be closed. The water in the settling-tank, screen-cylinder tank, and sluice will thus be maintained at substantially a uniform level, and all waste from absorption, evaporation, or other cause compensated 45 for automatically. The tank P or its equivalent may be kept supplied in any suitable manner.

The several shafts named are geared to the main driving-shaft C, as shown, or in any suitable manner, and may be geared thereto, to be 50 operated at any desired speed.

It will be seen that when in operation the pulverized earth or slime in the screen-cylinder tank will be continuously raised and carried up and out of the latter by the action of 55 the buckets on the screen-cylinder, and that in this operation a good deal of water, where water is used, will be carried with the earth and deposited upon the concave, and thence carried into the sluice-pan, and the water in 60 the latter, being thus raised above its normal level, will flow thence through the pipe m' into

the settling-tank, from which the screen-cylinder tank takes its supply. In this movement of the water the lighter particles, or what 70 is termed the "flour" or "float" gold, will be caught and held by the spiral amalgamating plate or plates in the passage of the water through their containing-tubes, and may be thence removed at suitable intervals. 75

The operation of the other devices will be readily understood. When water is not used, the settling and supply water-tanks will not be needed, and the placer-earth will be run dry through the screen-cylinder casing, thence 80 to the concave grinding-cylinder and sluice-pan, and will be operated upon in the same manner by said parts as in using them with water.

In using the machine dry or without water, 85 the flour gold of course will be lost, as that can be saved only by the use of the settling-tank with its water-ways and spiral amalgamating-plates, but the material will be otherwise acted upon and agitated the same as when 90 the water is used, and in such agitation, the gold being heavier than the other material passing over the sluice-pan, the particles thereof will gradually settle to and lodge upon the corrugated bottom of said pan, from which 95 it can be removed at suitable intervals, while the other material will be gradually discharged from the sluice by the action of the scrapers. 100

Having now described my invention, I claim as new—

1. In a machine for separating gold, the screen cylinder provided with the hollow trunnions, the outer right and left spiral flanges or threads, and central discharging-buckets, substantially as described. 105

2. The combination, with the screen-cylinder tank or casing and the screen-cylinder provided with its discharging-buckets, of the concave receiving-apron provided with its springs, and the grinding wheel or cylinder 110 operating in connection therewith, substantially as described.

3. The swinging links and sluice-pan suspended thereon, in combination with the cranks and connecting-rods for giving to said 115 pan both a longitudinal and a lateral reciprocating movement, substantially as described.

4. The herein-described gold-separating machine, comprising the inclined vibrating sluice-pan, the grinding concave receiving-apron, 120 the grinding-cylinder, and the intermittently-acting scrapers, arranged and operating substantially as described.

5. The combination, with the sluice-pan, of the reciprocating scraper bars or beams, and 125 the scraper having a spring-connection therewith, substantially as described.

6. The combination, with the scraper-bars, of the scrapers adapted to yield relatively to said bars, and means, substantially as described, for adjusting the scrapers.

7. The combination, with the sluice-pan, of the reciprocating scraper-bars, the side rails for said bars, and the tramways for lifting the

scraper-bars in their backward or return movement, substantially as described.

8. The combination of the screen-cylinder tank, the sluice-pan, and the settling-tank, and 5 pipes connecting said tanks and pan, substantially as described.

9. The combination of the vibrating sluice-pan, the settling-tank, and the flexible pipe or tube interposed between said pan and tank, 10 substantially as described.

10. A gold-separating machine comprising the screen-cylinder tank, the vibrating sluice-pan, the connecting concave or apron connecting said tank or pan, and the scrapers operating in the vibrating sluice-pan, substantially 15 as described.

11. The combination, in an apparatus for separating gold, of the screen-cylinder tank and sluice-pan, the settling-tank connected 20 therewith, a tubular water-way connected with said tank, and a spiral amalgamating-plate arranged within said way, substantially as described.

12. The combination, in an apparatus for 25 separating gold, of the screen-cylinder tank, the sluice-pan, and the settling-tank connected

therewith and provided with a central partition, a tubular water-way penetrating said partition, and a spiral amalgamating-plate arranged in said water-way, substantially as de- 30 scribed.

13. The combination, in a machine for separating gold, of the settling-tank, a supply tank or reservoir, and means, substantially as described, for automatically controlling the 35 water-supply and replenishing the settling-tank, substantially as described.

14. The combination, in a machine for separating gold, of the screen-cylinder tank, the sluice-pan, the settling-tank, the supply-tank, 40 and means, substantially as described, for connecting said supply-tank, settling-tank, screen-cylinder tank and sluice-pan, and maintaining a substantially uniform level of the water therein, substantially as described.

In testimony whereof I have hereunto set my hand this 13th day of March, A. D. 1885.

JAMES E. WESTLAKE.
